OUTBOARD MOTOR PROPELLER HUB UNIT

Lester R. Conrad, Fairview Park, Ohio

Application June 16, 1952, Serial No. 20,219

Term of patent 14 years

(Cl. D71—1)

To all whom it may concern:

Be it known that I, Lester R. Conrad, a citizen of the United States, residing at Fairview Park, in the county of Cuyahoga and State of Ohio, have invented a new, original, and ornamental Design for an Outboard Motor Propeller Hub Unit, of which the following is a specification, reference being had to the accompanying drawing, forming a part thereof.

Figure 1 is a perspective view of an outboard motor propeller hub unit embodying my new design;

Figure 2 is a side elevation of the hub unit; Figure 3 is a front view of the hub unit; and Figure 4 is a plan view of the hub unit.

The dotted lines on the drawing are for illustrative purposes only.

I claim:

The ornamental design for an outboard motor propeller hub unit, substantially as shown and described.

LESTER R. CONRAD.
